PROPELLER MOUNTING FOR TOY AIRPLANES

Nevilles E. Walker, Portland, Oreg.

Application February 19, 1938, Serial No. 191,461

12 Claims. (Cl. 46—78)

My invention relates to toy airplanes and particularly to that type in which a double-bladed propeller is carried upon one end of a propeller shaft and the other end of said propeller shaft is provided with means to which a rubber band motor may be attached so that said propeller shaft and said propeller can be rotated by the twisted rubber band. It is desirable that the propeller be directly connected to said shaft and it is desirable that the propeller be not pierced to receive said shaft. It is essential that the point of engagement of the propeller shaft be coaxial with the axis of rotation of said shaft so that said propeller will rotate without gyration.

15 The object of my invention is to provide a simple and efficient mounting which will securely hold the propeller in place, may be inexpensively manufactured and assembled, and be susceptible of quantity production.

20 The object of my invention is attained by providing a toy airplane with a metallic nose piece for the body thereof and with a propeller shaft mounted in said nose piece. One end of said propeller shaft is joined to the rubber band motor for said toy airplane and the other is joined to the propeller. Said propeller shaft preferably is made of an integral section of flat material, preferably half-round in section, which is bent back upon itself, with the loop thus formed straddling the propeller blade. Said flattened material is thus arranged so that the flat face of said section of material is bent back to oppose itself and to engage the sides of the propeller within the bight thus formed. I preferably force a washer tightly about said propeller shaft thus made and into close abutment with one edge of the propeller blade. The means of attachment for the rubber band motor is preferably formed directly in the shaft thus formed which holds the free end of said bent section of material together to prevent said end from spreading apart.

25 My invention is hereinafter described in greater detail in connection with a statement of further features thereof and in connection with the accompanying drawing in which:

Fig. 1 is an elevation of a toy airplane embodying my invention, with a portion of said airplane being shown broken away to disclose details which would otherwise be concealed;

30 Fig. 2 is an enlarged longitudinal section taken on line 2—2 in Fig. 3 thru the nose piece and the propeller of an airplane embodying my invention, and alongside the propeller shaft journaled in said nose piece;

Fig. 3 is an elevation taken on the line 3—3 in Fig. 2;

Fig. 4 is a larger scaled perspective detail, illustrating the looped end of the propeller shaft which encircles and engages the sides of a propeller blade, showing the manner in which a locking washer is arranged tightly against the inner end of the loop thus formed; and

Fig. 5 is a more or less diagrammatic view, illustrating the manner in which a pair of pincers 10 may be arranged to seat said washer in position and bind the looped end of the propeller shaft tightly against the side, faces and edges of a propeller blade.

A toy airplane embodying my invention comprises a body *a*, provided with a transverse wing element *b*, a propeller *c*, a rubber band motor *d* secured at one end to a hook *e*, and at the other end to the formed end *f'* of propeller shaft *f*. Said propeller shaft is preferably circular in section and is journalled in a metallic nose piece *g* seated in and sealing the forward end of said airplane body *a*. Said nose piece preferably comprises a shell *g'* and a disc *g''*. Said disc is preferably held in place in said shell by the crimped end *g'''* of the shell, being bent inwardly to a smaller diameter to hold said disc in place. The disc *g'''* is pierced at its center as at *g''*, with a hole sufficiently large only to accommodate the shank portion *f2* of the propeller shaft. The propeller shaft is also journalled in an aperture *g5* formed in the point of the shell *g'*. Said aperture *g5* and the pierced portion *g''* in the disc are alined and extend axially of the nose piece and constitute spaced bearings for the propeller shaft.

Said propeller shaft is preferably formed of a section of half-round wire, bent back upon itself, constituting two lengths. The flattened faces of said half-round wire are arranged in abutment with each other so that the shank of said propeller shaft is circular in section, as is shown in Fig. 4. As has been pointed out, the end *f'* is formed into a hook adapted to hold the forward end of the rubber band motor *d*. The other end of said propeller shaft is looped about the central portion of the propeller in a loop *f3*. Said loop *f3* is formed tightly about the faces of the propeller blade and about the edges thereof. That is, the loop is formed tightly about the portion of the propeller blade which it encircles, and said close fit is formed in part and maintained by a washer *h* seated upon the shank portion *f2* of the propeller shaft immediately adjacent the inner end of the loop *f3*.

Said washer is moved into place preferably under substantial pressure, as is diagrammatically illustrated in Fig. 5, being produced by a pair of pincers *i*. One of the jaws *i*' of said pincer is bifurcated and straddles the shank portion *f*2 of the propeller shaft and is arranged outside of the washer. The other jaw *i*2 is solid and is arranged to overlie the end of the loop *f*3 previously formed within the bight of the bent over section of material constituting the propeller shaft. Pressure is then exerted upon the pincers and the washer is forced up the shank, tightly against the loop, which is closed tightly about the propeller blade *c*. Sufficient pressure is produced to seat the washer tightly in place. Thus, the opposed lengths of the piece of material constituting said propeller shaft are held tightly against each other within the bore of the washer *h*. The other end of the shank which is formed into the end *f*' is held against disengagement because the loop is formed transversely to the plane of flattened faces of the lengths of material making said propeller shaft, and thus said lengths of material are prevented from separating from each other, as is shown in Fig. 2.

I preferably arrange a semi-spherical washer *j* between the outer face of shell *g*' and the washer *h* so as to minimize the area of contact against said washer, and thus decrease the frictional engagement of said washer with the nose piece.

When said washer has been seated tightly in place, and the pincers released, I preferably apply a layer of glue, as at *k*, over the looped portion *f*3 of the propeller shaft, the washer and the adjacent portions of the propeller so as to hold the propeller, said loop and said washer in the positions at which they are arranged when the pincers seat the washer tightly in place. I find that the washer stays in place moderately well without glue, but when held by a layer of glue, the maintenance of said relative position is assured.

I claim:

1. In constructing a mounting for the propeller of a toy airplane, the method steps comprising bending an elongated section of flat-faced material back upon itself with the flattened faces opposing each other, arranging a propeller blade within the bight thus formed, and forcing a close-fitting washer element longitudinally over said bent material with such force as to crimp the latter tightly against the edges of said propeller and to wedge the washer element in place.

2. In constructing a mounting for the propeller of a toy airplane the method steps comprising bending an elongated section of flat-faced material back upon itself with the flattened faces opposing each other, arranging a propeller blade within the bight thus formed, forcing a close-fitting washer element longitudinally over said bent material with such force as to crimp the latter tightly against the edges of said propeller and to wedge the washer element in place, and applying a coating of glue over said bent material and the adjacent portions of the propeller to hold said parts in seated engagement.

3. In constructing a mounting for the propeller of a toy airplane the method steps comprising bending an elongated section of flat-faced material back upon itself with the flattened faces opposing each other, arranging a propeller blade within the bight thus formed, forcing a close-fitting washer element longitudinally over said bent material with such force as to crimp the latter

tightly against the edges of said propeller and to wedge the washer element in place, and applying a coating of glue over said bent material and the adjacent portions of the propeller and the washer element to hold said parts in seated engagement. 5

4. In constructing a mounting for the propeller of a toy airplane the method steps comprising bending an elongated section of half-round material back upon itself with the flattened faces opposing each other, arranging a propeller blade 10 within the bight thus formed, and forcing a close-fitting washer element longitudinally over said bent material with such force as to crimp the latter tightly against the edges of said propeller and to wedge the washer element in place. 15

5. In a toy airplane, a body, a propeller, a motor for rotating said propeller, a nose piece for said body and a propeller shaft joining said motor to said propeller, said propeller shaft being journaled in said nose piece, said shaft comprising 20 an elongated section of half-round material doubled back upon itself to define an element of circular section, said half-round material being looped about and engaging said propeller within the bight thus formed, with the flattened sides 25 thereof abutting against the faces of said propeller and each other, respectively.

6. In a toy airplane, a body, a propeller, a motor for rotating said propeller, a nose piece for said body, and a propeller shaft joining said motor to said propeller, said propeller shaft being journaled in said nose piece, said shaft comprising 30 an elongated section of half-round material doubled back upon itself to define an element of circular section, said half-round material being looped about and engaging said propeller within the bight thus formed, with the flattened sides thereof abutting against the faces of said propeller and each other, respectively, and a washer 35 forcibly seated against said looped portion to hold the latter in tight engagement with the edges of said propeller.

7. In a toy airplane, a body, a propeller, a motor for rotating said propeller, a nose piece for said body, and a propeller shaft joining said motor to said propeller, said nose piece having a plurality of spaced lateral webs formed therein, said propeller shaft being journaled in the web portions of said nose piece, said shaft comprising an elongated section of half-round material doubled 50 back upon itself to define an element of circular section, said half-round material being looped about and engaging said propeller within the bight thus formed; with the flattened sides thereof abutting against the faces of said propeller and each other, respectively. 55

8. In a toy airplane, a body, a propeller, an elastic band motor for rotating said propeller, a metallic nose piece for said body, and a propeller shaft joining said band motor to said propeller, said nose piece having a plurality of spaced lateral webs formed therein, said propeller shaft being journaled in the web portions of said nose piece, said shaft comprising an elongated section of half-round material doubled back upon itself to 60 define an element of circular section, said half-round material being looped about and engaging said propeller within the bight thus formed; with the flattened sides thereof abutting against the faces of said propeller and each other, respectively, and a washer forcibly seated against said looped portion to hold the latter in tight engagement with the edges of said propeller. 65

9. A propeller mounting for airplanes comprising a nose piece for the forward end of an air- 70

75

- plane body, a propeller and a propeller shaft journalled in said nose piece, said shaft engaging said propeller by one end of said shaft and provided with a formed attachment means for a band motor at the other end thereof, said shaft comprising two lengths of an elongated section of half-round material lying alongside each other with the flattened faces of said half-round material opposing each other and engaging the opposite sides of the propeller, and at a point distant from said propeller abutting against each other and together constituting a shaft of circular section.
10. A propeller mounting for toy airplanes comprising a nose piece for the forward end of an airplane body, a propeller and a propeller shaft journalled in said nose piece, said shaft engaging said propeller by one end of said shaft and provided with a formed attachment means for a band motor at the other end thereof, said shaft comprising two lengths of an elongated section of flattened material, lying alongside each other, the attachment means engaging one end of the lengths to hold said flattened faces thereof in abutting relation with each other.
15. A propeller mounting for toy airplanes comprising a nose piece for the forward end of an airplane body, a propeller and a propeller shaft journalled in said nose piece, said shaft engaging said propeller by one end of said shaft and provided with a formed attachment means for a band motor at the other end thereof, said shaft comprising two lengths of an elongated section of flattened material, lying alongside each other, and comprising a single piece of material bent back upon itself to constitute said two lengths, and together constituting a shaft of circular section, said section of half-round material being looped about and engaging said propeller in the bight thus formed with the flattened sides thereof adjacent the bend abutting against the faces of the propeller and the remainder abutting against the opposed flattened faces of the two lengths, respectively, and a washer closely encircling said abutting lengths adjacent the looped portion of said section to hold the latter in tight engagement with the faces of said propeller.
20. A propeller mounting for toy airplanes comprising a nose piece for the forward end of an airplane body, a propeller and a propeller shaft journalled in said nose piece, said shaft engaging said propeller by one end of said shaft and provided with a formed attachment means for a band motor at the other end thereof, said shaft comprising two lengths of an elongated section of flattened material, lying alongside each other, and comprising a single piece of material bent back upon itself to constitute said two lengths, and together constituting a shaft of circular section, said section of half-round material being looped about and engaging said propeller in the bight thus formed with the flattened sides thereof adjacent the bend abutting against the faces of the propeller and the remainder abutting against the opposed flattened faces of the two lengths, respectively, and a washer closely encircling said abutting lengths adjacent the looped portion of said section to hold the latter in tight engagement with the faces of said propeller.
25. A propeller mounting for toy airplanes comprising a nose piece for the forward end of an airplane body, a propeller and a propeller shaft journalled in said nose piece, said shaft engaging said propeller by one end of said shaft and provided with a formed attachment means for a band motor at the other end thereof, said shaft comprising two lengths of an elongated section of flattened material, lying alongside each other, and comprising a single piece of material bent back upon itself to constitute said two lengths, and together constituting a shaft of circular section, said section of half-round material being looped about and engaging said propeller in the bight thus formed with the flattened sides thereof adjacent the bend abutting against the faces of the propeller and the remainder abutting against the opposed flattened faces of the two lengths, respectively, and a washer closely encircling said abutting lengths adjacent the looped portion of said section to hold the latter in tight engagement with the faces of said propeller.

NEVILLE S. WALKER. 35
